DESIGN FOR A TEXTILE FABRIC OR SIMILAR ARTICLE

Mark Turpan, West Englewood, N. J.

Application October 4, 1941, Serial No. 103,631

Term of patent 3½ years

To all whom it may concern:

Be it known that I, Mark Turpan, a citizen of the United States, residing in West Englewood, county of Bergen, and State of New Jersey, have invented a new, original, and ornamental Design for a Textile Fabric or Similar Article, of which the following is a specification, reference being had to the accompanying drawing, forming part thereof.

The figure of the drawing is a plan view of a textile fabric showing my new design.

I claim:

The ornamental design for a textile fabric or similar article, as shown.

MARK TURPAN.
